METHOD AND APPARATUS FOR APPLYING
CLOSURES TO CONTAINERSEmerson E. Hogg, New Kensington, Pa., assignor
to Aluminum Company of America, Pittsburgh,
Pa., a corporation of Pennsylvania

Application May 13, 1933, Serial No. 670,925

15 Claims. (Cl. 226—85)

This invention relates to methods and apparatus for applying closures or caps to containers.

Although the invention herein described and claimed may have other uses, it is particularly described with reference to the sealing of containers with closures composed of thin, flexible, and inherently fragile metal foil, or similar deformable material.

The packaging of foods or other substances in glass containers by sealing the container with metal foil has recently found considerable favor. The use of closures made of thin, flexible, and inherently fragile metal foil has introduced new problems into the art of sealing containers, which problems it is the general object of this invention to solve. While the invention is particularly adapted to the sealing of comparatively wide mouth containers of the thin-blown glass variety, such as glass tumblers, with a preformed closure composed of metal foil, the methods and apparatus of the invention are readily adaptable to the application, to any type of container, of closures which are characterized by their inherent weakness and frangibility.

The packaging of foods or other substances in wide mouth glass containers which, after the contents thereof are removed, may be used by the ultimate buyer as a drinking glass, or for other and similar domestic purposes, is gaining widespread use today. In order to meet its ultimate purpose, the wide mouth glass container is usually light and thin-walled. It has also a smooth exterior and interior glass finish adjacent its mouth or open end, and is characterized by the absence of any sharply projecting bead or thread or other formation which would interfere with the container being used for drinking purposes. Instead of the usual bead or thread with which glass containers are commonly finished for the purpose of facilitating the securing of a closure thereto, these particular thin-blown, wide mouth glass containers are provided with a glass finish, the exterior diameter of which is slightly greater than the container adjacent and immediately below the glass finish. Exemplary of one type of glass finish contemplated by this invention is a bead slightly larger in cross section than the wall thickness of its container. Another commercial form of finish adaptable to the principles of my invention is one which incorporates a flared portion around the periphery of the container opening.

When applying inherently fragile, preformed, metallic foil closures to commercial glass finishes incorporated in thin-blown glass tumblers, there is considerable difficulty in rapidly and commercially producing a seal or bond between these two inherently fragile articles. A further disadvantage encountered is the result of the above-mentioned absence from the finish of the con-

tainer of any sharp or abrupt formation upon which, or around which, the closure may be secured, thus enhancing the difficulty of effecting a tight and efficient seal between the closure and container. Also thin-walled glass containers of the type referred to cannot be economically manufactured within close dimensional tolerances and, therefore, the opening which must be sealed is often of variant diameter, the variation being often as much as three-thirty-seconds of an inch.

It is the general object of this invention to provide methods and apparatus by means of which a preformed inherently fragile closure may be secured to the glass finish of a comparatively wide mouth container.

A particular object of the invention is the provision of a method and apparatus which will substantially meet the difficulties hereinabove mentioned in connection with the securing of a preformed inherently fragile, metallic foil closure upon the glass finish of an inherently fragile thin-walled glass container.

A further object of the invention is to provide a closure-applying apparatus which is simple in construction and which may be used for the manual application of preformed metallic foil closures to glass finishes incorporated in containers of any sort.

A further object of the invention is the provision of a closure-applying apparatus incorporating a sealing head automatically adjustable to adaptation to commercial tolerances in container finishes and incorporating resilient means for applying pressure to the sealing head to insure against breaking of the containers during a closure-applying operation.

A further object of the invention is to provide new and efficient methods of forming tight and effective seals between the relatively smooth walls of a container and a preformed metallic foil closure applied thereto.

A further object of the invention is to provide a closure-applying mechanism which includes, in its organization, a resilient pressure-applying device which provides a resilient support upon the interior surface of the container being sealed during a closure-applying operation.

The above and other objects and advantages will be more clearly understood on consideration of the following description, the appended claims, and the accompanying drawings in which:

Fig. 1 represents, in side elevation, a closure-applying mechanism embodying the methods and principles of my invention, the sealing head being shown in a position just prior to a closure-applying operation;

Fig. 19 represents, in sectional elevation, a sealing head incorporating a modification of the pressure-applying disc shown in Fig. 11 as applying a deep-skirted fragile, metallic foil closure to a standard milk bottle finish.

Similar reference characters refer to like elements throughout the following description and in the drawings.

While the invention may be used in connection with many different container variations, it will herein be described with particular reference to the container and closure illustrated in connection with the closure mechanism in Figs. 1 to 9 inclusive.

The invention is predicated upon a method and apparatus for applying inherently fragile and flexible metal foil closures, comprising a top or body portion and a skirt portion, to the various glass finishes of containers, which method comprises resiliently pressing a portion of the body portion of said closure into close contact with the surface of the glass finish of the container and simultaneously or immediately thereafter resiliently and downwardly rolling the skirt portion of said closure into close and smooth conformity with the exterior surface of the glass finish of said container. In the more preferred form, the methods of my invention comprise applying and securing a preformed metal foil closure to the glass finish of a container by means of exerting a resilient pressure interiorly of the open end of the container to support the same and compress the closure into close conformity with the container opening interiorly thereof, and simultaneously, resiliently and downwardly rolling the cap into close conformity with the glass finish of the container opening exteriorly thereof. These and other methods of the inven-

tion will now be explained with reference to the apparatus shown in the drawings.

Referring to the drawings, the closure-applying mechanism illustrated therein comprises a base member or portion 10 having a vertical standard 11 formed integral with and terminating at its upper end in a suitable boss 12 provided with a bearing or bore 14 substantially centered with respect to the base. A shaft or stem 15 reciprocally mounted within the bore 14 is actuated through the medium of the rack teeth 16 by the action of a pinion formed on the cross shaft 18, which operates within the bore 17, extending through the boss 12. A shaft-locking and adjusting member in the form of a plate 20 pivotally attached to a machined surface on the boss 12, by means of a set screw 21, is adapted to enter the peripheral groove 22 in the exteriorly extending end of the shaft 18 whereby the shaft is locked or restrained against axial movement and the engagement of the pinion teeth 19 and the rack teeth 16 is insured, as is likewise a definite relationship between the base 10 and the elevation of shaft 15 for any and all positions of the pinion 19. An operating lever or handle 24 secured to the extending end of shaft 18 provides means for rotating the pinion 19 and reciprocating the shaft 15. The lever is preferably constructed from suitable flexible material, such as spring steel, and in the apparatus shown a loop 25 is provided intermediate the ends of the handle to insure such flexibility that the handle will yield under pressure.

A sealing head represented in entirety by the reference character 26 is detachably secured to the lower end of shaft 15. The head comprises a cylindrical cup-shaped housing having a top portion 27 and a depending cylindrical skirt portion 28. A boss 29 integral with the top portion and provided with a suitable bore 30 provides means for receiving the undercut lower end 13 of the shaft 15. A set screw 31 threaded into the boss 29 and extending therethrough enters an annular groove 32 provided in the shaft 15, thus constituting a detachable mounting for the sealing head. The interior of the sealing head is formed with an annular groove 34 adjacent the lower edge of the skirt 28. This groove terminates in a relatively small inturned flange 35 on the extreme bottom edge of the skirt and the upper edge of said groove curves inwardly as at 36 into tangential coincidence with the interior thickened wall 37 of the sealing head housing. Within the groove 34 there is retained, by means of the flange 35, a resilient and plastic pressure-applying or sealing disc 38 made of rubber or other suitable plastic material. This pressure-applying disc is preferably, but not necessarily, symmetrical around a horizontal center line so that it may be turned over or reversed within the groove 34 as one face of the disc becomes worn.

The pressure-applying disc is provided around its outer periphery with a narrow flange 39 of substantially the same diameter and cross section as that of the groove 34. While, in accordance with the principles of the invention, this disc may take different forms, in the form here shown the disc swells appreciably from the flange 39 into a bulbous formation 40 of substantially circular cross section, said bulbous portion being attached to the main body portion 41 of the disc through a reduced section formed by the grooves 42. A central disc aperture 43 insures maximum flexibility of the body portion of the disc and in order to allow contraction, the periphery of the sealing

disc is provided with a plurality of radial slots 44 which extend to an appreciable distance within the bulbous portion 40.

Adjacent the base 10, the closure-applying assembly is provided with a container-centering device which may take any suitable form but is herein shown in the form of cap screws 45 which extend through threaded apertures in webs 46 formed integral with the base and the standard 10 11. Lock nuts 47 provided on the threaded shanks of the bolts 45 provide means for locking the same in adjusted position. A resilient pad 48 on the base 10 insures a resilient support for the container supported thereon during the cap- 15 applying operation.

The operation of the improved closure-applying mechanism just described will be explained with reference to a container of the type shown in Figs. 1, 5, and 6. This container, 50, is of 20 glass and has a relatively thin wall. Adjacent its open end it is almost devoid of means upon which to lock a closure, except for the relatively small bead 55. By means of the centering screws 45 the axis of the container is aligned with that 25 of the sealing head 26, and upon the open end of the container is placed a fragile metal foil cap, in this instance having a depressed central portion 52, designed to contact with the minimum diameter of the interior of the container opening, 30 and a coextensive grooved flange 53 and depending skirt 54 which loosely enclose the bead 55 and an exterior portion of the container below said bead. The sealing head 26 is lowered from 35 the position shown in dotted lines (Fig. 1), wherein in the operating lever 24 abuts against the lug 56 formed integral with the standard 11, into a position wherein the head is supported by the loosely capped container (Figs. 1 and 5). In this position the operating lever 24 should extend substantially horizontally, and if such is not the case, such 40 positioning may be obtained by a proper manipulation of the plate 20 and the relative rotation of the pinion 19 with respect to the rack 16. Pressure is now applied to the handle 24 with the 45 following results. First, the closure is resiliently pressed against the glass finish of the container interiorly the opening thereof, the central portion 41 of the sealing disc providing a resilient support within the open end of the container 50 and also 50 compressing the closure into close conformity with the interior of the glass finish. Immediately thereafter or simultaneously therewith the sealing disc 38 is interrupted in its downward movement and progressively assumes a configuration 55 such as that shown at Fig. 6, the bulbous portion 40 being progressively rolled by the deforming downward action of the sealing head 26 into close contact with the skirt of the closure, thereby 60 resiliently and downwardly rolling the skirt of said closure into close and smooth conformity with the bead 55 and the exterior wall of the container immediately below said bead. During this sealing operation air entrapped within the sealing head escapes through the apertures 43 and 59.

Referring specifically to the particular manner in which the sealing head functions in performing a sealing or closure-applying operation on a thin-blown glass tumbler, it will be noted that the 65 groove 42 of the pressure-applying disc 38 (Fig. 5) coincides with and loosely receives the grooved flange 53 of a cap supported upon the open end of a container, the groove 42 being properly selected to accommodate the maximum and minimum 70 commercial glass finishes. As the pressure is ap-

plied by lowering the handle from its horizontal position (Fig. 1), the sealing disc 38 is deformed by the curved portion 36 (Fig. 6) of the sealing head bearing upon the bulbous portion 40 thereof, and the upper surface of the disc 38 5 coming in contact with the interior flat machined surface 58 of the sealing head. This action causes the interior portion 41 of the disc to enter and resiliently clamp or compress the central depressed portion of the closure into close 10 conformity and contact with a substantial portion of the interior surface of the glass finish of the container 50, the interior contact between the closure and glass finish, in the particular illustration in Fig. 6, terminating approximately 15 in a plane intersecting the bead 55 on its horizontal diameter. The bulbous portion 40 simultaneously compresses the material of the closure constituting the annular grooved flange 53 and depending skirt 54 into close contact with the exterior glass finish and any minute irregularities incorporated therein, and a portion of the tumbler wall below said glass finish, by a downward rolling action which progressively and resiliently smooths the closure into close conformity with 20 the exterior glass finish of the container. Against this exterior pressure created by the downward rolling action of the bulbous portion 40 the tumbler is resiliently supported interiorly of its opening by the central depressed portion 41 of 25 the pressure-applying disc, which function of the sealing disc 38 insures against fracture of the relatively thin-walled tumbler. During this rolling operation or deformation of the disc 38 into 30 cap sealing position (Fig. 6), the periphery of the 35 disc is of necessity contracted by compression and recedes from the groove 34. The slots 44 function to assist this contraction and thereby insure a closer contact between the glass finish and the cap, resulting in less pressure being required 40 to perform a closure-applying operation.

The preferred method above described and employed in performing a closure-applying operation comprises the steps of providing a cap which 45 loosely embraces the opening in a container exteriorly and interiorly thereof. Thereafter pressure is applied to said cap and container by means of a resilient pressure-applying disc which engages the cap interiorly and exteriorly of said 50 container opening, the applied pressure being initially applied coincident with the axis of the container, but through the formation of the sealing head and rubber sealing disc, resolved into a compressive force which rolls the peripheral portion of the pressure-applying disc downwardly into 55 smooth, close conformity with the container finish. It will be readily appreciated that the rolling action of the bulbous portion of the rubber pressure-applying disc compresses the material of the cap into close contact with the exterior 60 portion of the bead and that portion of the container below the same, whereas the central portion of the disc applies as resilient pressure against that portion of the closure in contact with the interior portion of the glass finish of the container 65 opening and resiliently supports the same against breakage. The pressure applied by the pressure-applying disc is therefore normal to the glass finish surrounding the container opening at all points, the arc of contact between the closure and bead being greater than 180° (Fig. 6). Referring to Fig. 12, a fragmentary view of a tumbler 60 is shown having a flared glass finish 61 adjacent its open end. A closure 62 similar to that described in connection with tumbler 50 is 75

secured interiorly and exteriorly to the glass finish of tumbler 60, the apparatus shown in Fig. 6 being adaptable to the closure-applying operation providing the annular groove 42 permits embracing the closure and glass finish in the manner described heretofore in connection with tumbler 50.

Up to this point, in the explanation of the invention, a method and apparatus have been described in connection with the application of fragile, metallic foil closures to relatively wide mouth containers or receptacles, such as tumblers, which are characterized by their inherent weakness and which are furthermore substantially free from glass finishes incorporating abrupt formations or other closure-securing means adjacent their open ends. It is within the realm of this invention, however, to apply closures of the general type previously described to a variety of receptacles incorporating various other forms of glass finishes of which Figs. 13 to 17 inclusive are exemplary. In these examples the receptacles are relatively heavy as compared to thin-blown glass tumblers, but the method and apparatus previously described are readily adaptable to operation on such containers.

Referring in more particularity to Figs. 13 through 16, receptacles are shown to which closures, having top portions 64 and depending skirts 65, are secured. These closures are of the same general type as that shown in Fig. 6 and are constructed with an annular groove 66 in their top surfaces which provides a contacting portion on the interior surface of each of the receptacles adjacent the open ends thereof.

The application of the closures to the receptacles illustrated in Figs. 13 to 16 inclusive is accomplished by means of employing the resilient pressure-applying or sealing disc 67 illustrated in Figs. 9, 10, and 18. Herein the sealing disc is provided with a body portion 68 and a depending flange 69 which terminates in a bulbous portion 70. As in the case of the sealing disc shown in Figs. 7 and 8, radial slots 71 and a central aperture 72 are provided. The interior upper surface of the sealing disc 67 is concave, as at 73, and an annular groove 74 and relief groove 75 are provided adjacent the depending flange 69 and on the interior surface thereof. As will be manifest from Fig. 18, the closure-applying operation, with respect to the various glass finishes illustrated in Figs. 13 through 16, is similar to that described in connection with Fig. 6, the closures being resiliently compressed interiorly the receptacle openings, by means of the particular concave portion 73 of the sealing disc 67, which conforms with the annular grooves 66 in the top surfaces of the closures, and the depending skirts 65 of the closures are simultaneously and progressively rolled downwardly, by means of the bulbous portion 70, under the action of the sealing head 76. Although the sealing operation shown in Fig. 18 is specific to the receptacle shown in Fig. 13, and the annular groove 74 with in the sealing disc 67 is constructed in a form suitable to embrace the particular glass finish of the receptacle of Fig. 13, it will be quite obvious to those versed in this art that the selection of the particular form of sealing disc will be governed by the glass finish with which it is to be employed. It is desirable, however, in the case of relatively heavy receptacles, to provide a relief groove, such as 75 (Fig. 10), adjacent the bulbous portion of the resilient sealing disc, particularly where the glass finish is of an abrupt nature and

the rolling deformation of the bulbous portion of the sealing disc is extreme as compared with the action of the sealing disc in the preferred form of the invention (Fig. 6).

In Figs. 11 and 17 a resilient sealing disc and fragmentary portion of a sealed receptacle are respectively illustrated. In this particular instance a closure having a substantially flat top surface 77 and depending skirt 78 is secured to a glass finish of substantially the milk bottle type. Herein there is no interior contact between the closure and glass finish and the sealing disc 79 for the application of this type of closure differs from that shown in Fig. 10 in that it is provided with a flat interior surface 80. In other respects the sealing disc 79 and its method of operation are similar to those previously described, the closure being resiliently compressed against the glass finish adjacent its top surface and simultaneously and resiliently rolled downwardly into close conformity with the exterior surface of the glass finish.

Fig. 19 discloses a fragmentary view of a closure-applying mechanism in which the method above described is carried out in connection with a milk bottle glass finish and a deep-skirted, fragile, metallic foil closure. Herein a sealing disc 81 similar to that shown in Fig. 11, but having a longer flange 82, is employed, the closure being resiliently compressed upon the top surface of the glass finish, as at 83, and the deep skirt 84 simultaneously and resiliently rolled into close conformity with the exterior glass finish and an appreciable portion of the exterior surface or neck of the bottle below the glass finish.

Heretofore containers or receptacles having abrupt and sharp finishes, such as those disclosed in Figs. 13 to 17 inclusive, were usually sealed by means of relatively heavy metal closures, or other types of closures, the depending skirts of which were spun or rolled into conformity with the glass finishes by a suitable tool adapted to operate in a plane at right angles to the axes of the containers. In some cases resilient pressure-applying rings were also employed for the purpose of radially compressing the skirts of closures into conformity with the exterior surfaces of container finishes. It will be readily seen, however, that closures made from fragile, metallic foil material, as contemplated by this invention, would not withstand a spinning or rolling operation applied in a plane at right angles to the axis of the container, to which such a closure was being applied, in view of the disastrous tearing and shearing effect of torsion applied to the skirt relative to its top portion. Furthermore, a radially applied compressive force, such as applied by a compression ring, does not insure the ironing and smoothing of the skirt material into close conformity with the glass finish of the container, as is possible with the methods and apparatus contemplated by this invention.

In this connection the resilient pressure on the top surface of a fragile metal foil closure, whether this pressure be applied interiorly of a container opening or at an exterior point on the top surface of the closure adjacent the skirt thereof, combined with the simultaneous and resilient downward rolling of the skirt of the closure into close conformity with the exterior glass finish of the container, insures sealing contact between a substantial portion of the top or depressed portion of a closure with its container finish, simultaneously with a progressive downward ironing and smoothing of the skirt into the irregularities

of the exterior container finish. With the apparatus and methods herein described the fragile metal foil closures are not subjected to spinning or rolling operations, which would rupture the material of the closures, but are applied in a manner to insure a good seal between the containers and closures with a minimum amount of work upon the closure material in performing the same.

It will be quite manifest, on consideration of the particular form of the plastic or resilient sealing discs and the cooperating housing members in which they are enclosed, that the pressure applied to the closures is plastic in nature and resolves itself from an original vertical pressure through the vertical axis of a container and closure to a pressure which is substantially normal at all points of contact of a closure with its container. The initial pressure on a sealing disc plastically engages the closure in contact with its container upon an upper surface thereof, and subsequent simultaneous pressure rolls the edge portion of the disc into plastic engagement with the depending skirt of the closure. The initial plastic engagement, in view of the form of the sealing discs above described, is relatively immovable, the bulbous edge portion of the disc exerting a rolling plastic pressure against the depending skirt of the closure.

Having thus described and explained the invention and its manner of operation, it is to be understood that the particular apparatus selected was merely for purposes of illustration and that modifications in the form and arrangement of parts shown and described herein may be made without departing from the nature and scope of the invention except as defined in the claims appended hereto.

What I claim is:

1. The method of applying a fragile metal foil closure to the glass finish of a container which comprises plastically pressing a portion of the closure into close conformity with the container finish interiorly thereof, and simultaneously, plastically and resiliently rolling the skirt of the closure downwardly and inwardly into close conformity with the exterior glass finish of the container, whereby the closure is resiliently held in contact with the container finish interiorly thereof and the closure skirt is progressively rolled downwardly and inwardly into close conformity with the exterior finish of the container.

2. The method of applying a closure to a container having a glass finish adapted to support a closure having a central depressed portion extending into said container and a coextensive grooved flange and depending skirt adapted to embrace the glass finish of the container, which comprises resiliently and plastically pressing the central depressed portion of the closure into close conformity with the glass finish interiorly thereof, simultaneously applying a substantially normal plastic pressure directly upon the coextensive grooved flange, and plastically rolling the depending skirt downwardly and inwardly into close conformity with the exterior glass finish of the container.

3. The method of applying a closure to a container having an open end provided with a glass finish in the form of a bead of substantially circular cross section, said closure having a central depressed portion and a coextensive grooved flange and depending skirt, which comprises resiliently and plastically pressing the central depressed portion of the closure into close con-

formity with the bead interiorly of the container opening, simultaneously applying a substantially normal plastic pressure directly upon the coextensive grooved flange, and plastically rolling the depending skirt downwardly and inwardly into close conformity with the bead and the container below the bead exteriorly of said opening.

4. The method of securing a fragile, metallic foil closure to the glass finish of a container which comprises exerting a resilient and plastic pressure interiorly the glass finish to support the same and compress a portion of a closure supported thereon into close conformity with the glass finish interiorly thereof, simultaneously applying a substantially normal plastic pressure directly upon the top surface of the closure to press the same into close conformity with the glass finish thereof, and resiliently rolling a skirt portion of said closure progressively downwardly and inwardly into close conformity with the glass finish exteriorly thereof.

5. In a closure-applying mechanism, a sealing head adapted to be reciprocated toward and away from a container having a closure loosely applied to its open end, plastic means within said sealing head for simultaneously engaging said closure adjacent a top and side surface thereof, said plastic means being adapted to relatively immovably engage and apply a direct and substantially normal pressure upon the top surface of the closure to compress the same into close conformity with the container opening, and means incorporated in said sealing head and adapted to engage the plastic means to plastically roll the side surface of the closure into close conformity with the container below said top surface.

6. A closure-applying mechanism comprising a reciprocally mounted sealing head adapted to move toward or away from a container in the process of applying a closure to the glass finish of an opening in said container, resilient means for reciprocating said sealing head, a plastic pressure-applying disc within said sealing head, and means associated with said sealing head adapted to exert a substantially normal pressure upon the plastic disc to relatively immovably engage and compress the closure into close conformity with the top surface of the container glass finish, and means incorporated in said sealing head for simultaneously deforming a peripheral edge of the plastic disc to roll a portion of the closure into close conformity with the container below said glass finish.

7. A closure-applying mechanism comprising a reciprocally mounted sealing head adapted for movement toward or away from a container in the process of applying a closure to an opening in said container, resilient means for reciprocating said sealing head, a resilient pressure-applying disc within said sealing head, said pressure-applying disc having a bulbous peripheral portion coextensive with its central portion and separated therefrom by an annular groove, and means incorporated in said sealing head and adapted on the application of pressure applied to said head to roll the closure into close conformity with said container opening.

8. A closure-applying mechanism comprising a reciprocally mounted sealing head, said sealing head being adapted to be moved toward and away from a container having a closure loosely supported upon its open end, means for reciprocating said sealing head, a pressure-applying disc within said sealing head, said pressure-

- 5 applying disc being formed with an annular groove adapted to loosely embrace the closure supported upon the container opening, and means associated with said sealing head whereby pressure applied thereto rolls the pressure-applying disc into close conformity with the closure to apply the same to the container opening.
9. A closure-applying mechanism comprising a reciprocally mounted sealing head, said sealing head being adapted to be moved toward and away from a container having a closure provided with a centrally depressed portion extending into the open end of the container and a coextensive grooved flange and skirt loosely embracing the container opening, a pressure-applying disc within said sealing head, said disc having a central body portion substantially the same dimensional size as the centrally depressed portion of the closure, and a bulbous peripheral portion separated from the central portion by a groove adapted to loosely embrace the grooved flange of the closure and the container opening, said pressure disc on application of pressure applied thereto, by the sealing head, being adapted to compress the closure into close conformity with the container opening exteriorly and interiorly thereof.
10. A closure-applying mechanism comprising a reciprocally mounted sealing head, said sealing head being adapted to be moved toward and away from a container having a closure provided with a central depressed portion extending into the open end of the container and a coextensive grooved flange and skirt loosely embracing the container opening, a stem attached to said sealing head, a pinion engaged with teeth formed on said stem, a handle for rotating said pinion and thereby reciprocating said stem, said handle being provided with a loop intermediate its ends to impart flexibility thereto, a pressure-applying disc within said sealing head, said disc having a central body portion substantially the same dimensional size as the centrally depressed portion of the closure, and a bulbous peripheral portion separated from the central portion by a groove adapted to loosely embrace the grooved flange of the closure and the container opening, said pressure disc on application of pressure applied thereto, by the sealing head, being adapted to compress the closure into close conformity with the container opening exteriorly and interiorly thereof.
11. A closure-applying mechanism comprising a reciprocally mounted sealing head, said sealing head being adapted to be moved toward and away from a container having a closure provided with a central depressed portion extending into the open end of the container and a coextensive grooved flange and skirt loosely embracing the container opening, a stem attached to said sealing head, a pinion engaged with teeth formed on said stem, a handle for rotating said pinion and thereby reciprocating said stem, said handle being provided with a loop intermediate its ends to impart flexibility thereto, a pressure-applying disc within said sealing head, said disc having a central body portion substantially the same dimensional size as the centrally depressed portion of the closure, and a bulbous peripheral portion separated from the central portion by a groove adapted to loosely embrace the grooved flange of the closure and the container opening, said pressure disc having radial slots in its periphery to permit contraction of the periphery of the disc, said pressure disc on application of pressure applied thereto, by the sealing head, being adapted to compress the closure into close conformity with the container opening exteriorly and interiorly thereof.
12. In a closure-applying mechanism, a sealing head adapted to be reciprocated toward and away from a container having a closure loosely applied to its open end, said closure engaging said container opening exteriorly and interiorly thereof, plastic deformable means in said sealing head for engaging the closure interiorly and exteriorly of said container opening, means within said sealing head for engaging the plastic deformable means in a closure-applying operation, said engaging means being adapted for engagement with the plastic means to exert a plastic pressure upon the closure interiorly of said container opening and simultaneously roll the closure into close conformity exteriorly of the container opening.
13. A closure-applying mechanism comprising a reciprocally mounted sealing head, said sealing head being adapted to be moved toward and away from a container having a closure provided with a centrally depressed portion extending into the open end of the container and a coextensive grooved flange and skirt embracing the glass finish around said container opening, a resilient pressure-applying disc within said sealing head, said disc having a central body portion adapted to extend into the centrally depressed portion of the closure, and said disc having a bulbous peripheral portion separated from the central portion by a groove adapted to embrace the grooved flange of the closure and the glass finish of the container, said sealing disc on application of pressure applied thereto, by the sealing head, being adapted to resiliently compress the centrally depressed portion of the closure into close conformity with the glass finish interiorly thereof and resiliently support the container against the simultaneous pressure exerted by the bulbous portion of the disc exteriorly the glass finish.
14. A plastic disc for applying closures to containers having a central body portion substantially the same dimensional size as a centrally depressed portion of a closure, a bulbous peripheral portion separated from said central portion by a groove adapted to loosely embrace a grooved flange coextensive with said closure, said plastic disc, upon application of pressure thereto, being adapted to compress the closure into close conformity with a container opening exteriorly and interiorly thereof.
15. The method of securing a fragile closure to the glass finish of a container, which comprises applying a plastic pressure to the portion of a closure to compress the same into close conformity with the glass finish interiorly of the opening of the container, simultaneously applying a substantially normal plastic pressure directly upon a top portion of the closure to compress the same into close conformity with the glass finish thereof, and simultaneously, plastically rolling a portion of the closure coextensive with said top portion downwardly and inwardly into close conformity with the glass finish of the container exteriorly of said opening.
